J. F. CASEY

MOLD

Filed July 29, 1925

INVENTOR
JOHN F. CASEY
BY C. F. Black ATTY.

UNITED STATES PATENT OFFICE.

JOHN F. CASEY, OF PORTLAND, OREGON.

MOLD.

Application filed July 29, 1925. Serial No. 46,903.

My invention relates to molds in general, and particularly to molds for producing concrete conduit such as is used for underground wiring, the object being to provide a device whereby such conduit may be manufactured of concrete poured into suitable sand molds, and thus be produced very cheaply.

I accomplish the above object by means of 10 the construction illustrated in the accompanying drawing, which is a part of this application for Letters Patent, like characters of reference indicating like parts throughout the several views thereof, and in which:

15 Fig. 1 is a sectional elevation in perspective of my mold after being rammed up.

Fig. 2 is a similar view of the same ready for the pouring of the concrete thereinto.

20 Fig. 3 is a perspective view of the core supporting grid.

Fig. 4 is a perspective view of the core print plate.

Fig. 5 is a perspective view of the pattern.

Fig. 6 is a perspective view of the core.

25 Fig. 7 is a perspective view of the product.

In general my device consists of the usual mold box with top and bottom boards, a stripping plate surrounding a pattern fixed upon one of said boards and said pattern having core prints thereupon; a core print plate imbedded in the mold; cores adapted to set into said core print plate and to extend above said stripping plate when the mold is 30 in position for the pouring of concrete thereinto; and a grid for supporting the projecting ends of said cores.

The mold box 8 may be of any convenient and suitable form, with flanges adapted to be 40 dowelled to a bottom board 9, said bottom board being provided with a pattern 10 secured thereto or made integral therewith, said pattern being shaped to the outer form of the conduit to be manufactured. A stripping plate 11 is provided and disposed between said box and said bottom board, receiving the dowels that secure said box and said board together, and said stripping plate is provided with an orifice therein adapted 45 to fit over the pattern 10. The edges of said orifice are beveled to coincide with the line of juncture of the pattern and the board 9 as shown in Figs. 1 and 2.

The pattern is provided with a plurality 50 of core prints 12, there being as many such core prints as there are channels in the con-

duit to be manufactured. A core print plate 13 is provided, and said plate has orifices 14 adapted to receive the core prints 12. When the bottom board with its attached 55 pattern is in place within the box 8 said core print plate 13 is placed upon the pattern 10 with the core prints 12 projecting through their respective orifices 14, as shown in Fig. 1, and sand is then rammed into the box 8 around the pattern 10, also as shown in Fig. 1. When the mold is properly rammed up a top board 15 is placed thereupon, and the entire mold is reversed into the position 60 shown in Fig. 2.

The bottom board 9 is then removed, withdrawing the pattern 10 therewith, and the cores 16 are set in place. Each of said cores 16 is provided with a core print 17 adapted to fit into the space left in the mold by the 65 core prints 12 of the pattern 10, and to project through the orifices 14 in the core print plate 13, as shown in Fig. 2.

The tops of the cores 16 are just level with the upper surface of the stripping 70 plate 11 when the mold is in pouring position as shown in Fig. 2, but a portion of each core projects above said stripping plate in the form of a pin 18, and a grid is provided to receive said pins 18 and thus to 75 steady and support the cores 16. Said grid consists conveniently of a boxlike frame 19 provided with flanges adapted to register with the flanges upon the mold box 8 and to be dowelled thereto, with the stripping 80 plate 11 disposed between said mold box and said grid, as shown in Fig. 2. Within said frame 19 are cross members 20 disposed so as to lie above the various cores 16, and having orifices 21 therein to receive the core 85 pins 18. Said cross members are disposed so as to allow concrete poured into the frame 19 to reach and enter the spaces around the cores 16, conveniently by being raised above the level of the top of the mold and the 90 cores, as shown in Fig. 2.

The conduit for which this device is designed to be used in manufacture is required to have holes 22 longitudinally disposed therethrough, and to provide for such holes 105 I place rods 23 in the mold, said rods entering orifices 24 in the cross members 20 of the grid, and corresponding orifices 25 in the core print plate 13.

When the concrete has been poured into 110 the mold positioned as shown in Fig. 2, the grid is removed therefrom, and the top

of the poured form is slicked off smoothly and even with the top of the stripping plate 11.

My device may be made of any size, and 5 constructed of any materials deemed convenient and suitable for a device of this character, and while I have illustrated and described a form of construction and arrangement of parts found desirable in materializing my invention, I wish to include 10 in this application all mechanical equivalents and substitutes that may fairly be considered to come within the scope and purview of my invention as defined in the appended claims.

Having disclosed my invention so that others may be enabled to construct and to use the same, what I claim as new, and desire to secure by Letters Patent is:

20 1. In a mold: a plurality of cores; core prints upon said cores; and a plate provided with orifices to receive said core prints, and adapted to be imbedded within the mold.

25 2. In a mold: a plurality of cores with oppositely projecting portions; a plate adapted to be imbedded within the mold and having orifices therein to receive certain of said projecting core portions; and a grid upon said mold provided with orifices for receiving the corresponding core portions.

30 3. In a mold: a board; a pattern secured upon said board; core prints upon said pat-

tern; and a plate provided with orifices adapted to receive said core prints, said plate being imbedded within the mold.

4. In a mold: a plate imbedded in the mold; a grid upon said mold; and cores positioned by the coaction of said plate and said grid.

40 5. In a mold: a plate imbedded in the mold; a grid upon said mold; cores positioned by the coaction of said plate and said grid; and rods positioned by said plate and said grid and disposed between certain of said cores.

6. In a mold: a plate imbedded in the mold and adapted to receive projecting portions of cores.

7. Means to position a core within a mold, 50 comprising a member imbedded within the mold and a member disposed above the mold, said members being adapted to hold a core positioned therebetween.

8. In a mold: a plate imbedded within 55 said mold; a box like frame upon said mold; cross members within said frame; cores positioned within said mold by certain of said cross members and said plate; and rods positioned within said mold by other 60 of said cross members and said plate.

In witness whereof I claim the foregoing as my own I hereunto affix my signature at Portland, county of Multnomah, State of Oregon, this 29th day of July, 1924.

JOHN F. CASEY.
